actuator 40c, thereby breaking the magnetic contact with the head 42c of actuator 40c and allowing the spring 44c to return the latter to the open circuit position, thereby turning off the lights, and leaving the lighting circuit open even when the door 14c is again closed.

FIG. 10 diagrammatically illustrates another embodiment of the invention wherein the automobile lights may be operated in conventional manner, with the present improvement being separately operable to bypass the light switch 60d and operate the automobile lights independently when switch 60d is in "off" position.

Referring more particularly to FIG. 10, it will be noted that there is a door operated circuit breaker or switch 20d, having an actuator button 86d corresponding in use to slide button 36 of FIG. 2, or pushbutton 86 of FIG. 7. The operation of actuator button 86d, closes the light circuit as described in connection with the combinations illustrated in FIGS. 2, 7 and 9, so that opening of the door 14d adjacent the driver will automatically open the light circuit and turn off the lights. Where a solenoid is used as previously described, wires 47d and 48d are used to supply electric current for the operation of same when pushbutton 86d is depressed.

Although certain preferred embodiments of the invention have been disclosed, it will be readily appreciated that other equivalent structures can be utilized to obtain the same results. For example, the magnet 52 need not be a permanent magnet but can be an electromagnet. Furthermore, the latching mechanism 50 need not be a magnet at all, but could instead be a mechanical catch or the like which engages the head 42 when fully extended and the door closed, but which breaks away from the head when the door is opened, and it is intended that the showing in the drawings be considered to diagrammatically illustrate the alternate elements described in this paragraph. Consequently, the preferred embodiments disclosed herein are not to be regarded as showing the only possible forms of the invention, but instead as illustrating the concepts underlying it.

I therefore particularly point out and distinctly claim as my invention:

1. In combination with a motor vehicle having a door and an electrical system including a battery, at least one headlight, and a light switch connected in a circuit including said battery and said headlight, an automatic headlight turnoff system comprising: a switch having terminal means connected into the headlight circuit to open and close the same and having a movable actuator means; means for mounting said actuator

means generally adjacent said door and movable with respect thereto; means for effectively latching said actuator means against said door when the latter is in a closed position; means for biasing said actuator means away from its said latched position when said door is opened; and means for moving said actuator means toward its said latched position against said biasing means.

2. The turnoff system as defined in claim 1, wherein said switch includes a housing portion and said actuator means includes a member extending outwardly of said housing.

3. The turnoff system as defined in claim 1, wherein said latching means includes a magnet and said actuator means carries a ferromagnetic portion to latch by magnetic attraction to said magnet.

15 4. The turnoff system as defined in claim 3, including means for mounting said magnet on said door.

5. The turnoff system as defined in claim 3, wherein said means for moving said actuator means includes a slide and a manually actuatable handle member.

20 6. The turnoff system as defined in claim 5, wherein said switch includes a movable contact carried by said slide and positioned to close a circuit across said terminal means only when said actuator means is latched by said latching means.

7. The turnoff system as defined in claim 1, wherein said 25 means for moving said actuator means includes a solenoid.

8. The turnoff system as defined in claim 7, wherein said actuator means comprises an armature for said solenoid.

9. The turnoff system as defined in claim 7, including a manually actuatable electrical switch for energizing said solenoid and means for biasing said switch normally in the open circuit position.

30 10. The turnoff system as defined in claim 1, wherein said turnoff system includes a first movable member (50c) mounted for movement toward and away from said door, means for biasing the movement of such member, and a second movable member (40c), and wherein said latching means (52c) holds said members in a predetermined mutual position in which the first member contacts said door.

11. The turnoff system as defined in claim 10, wherein said 35 latching means includes a magnet.

12. The turnoff system as defined in claim 11, wherein said magnet is carried by one of said movable members.

13. The turnoff system as defined in claim 10, wherein one of said movable members carries a movable contact comprising a part of said switch.

PATENTED OCT 5 1971

POWER SUPPLY

This invention relates to power supplies for television receivers.

In recent years, vacuum tube television receivers have employed instant-on circuits which apply reduced power to the vacuum tube filaments during a standby mode of operation. The warmup time of the instrument is thus greatly reduced when switched into operation. The reduced power during standby operation has been accomplished for example by placing a diode across the power switch. When in the standby operation has been accomplished for example by placing a diode across the power switch. When in the standby condition (power switch open) one-half wave rectified voltage is applied to the filaments. When in operation (power switch closed) the diode is electrically shorted and an alternating current delivers full power to the filaments. Other systems utilize the power supply rectifier diode and a double pole switch to couple the diode to the filament string during standby operation while simultaneously disconnecting the diode from the direct power output circuit. During operation, the diode is switched into the direct voltage power output circuit and the filament string is coupled to an alternating voltage. Common to both of these methods and other similar systems is the application of one-half wave rectified voltage to the filaments during standby operation and an alternating voltage (not rectified) to the filaments during normal operation. The circuitry of the present invention, however, supplies full-wave rectified direct voltage to the filaments during normal operation, and half-wave rectified voltage to the filaments during standby operation.

Operation of the filaments by full-wave rectified voltage is advantageous in that raster movement due to leakage of alternating power line frequency current between the filaments and cathodes of stages such as the horizontal oscillator is prevented. This movement can be particularly objectionable where the frequency of input power to the receiver varies considerably from the television field transmission rate, for example, when the power line frequency is 50 Hz. and the television field rate is 60 Hz.

Due to the reduced cost of solid state diodes, it is economically feasible to employ full-wave bridge rectifiers as the means for supplying the direct operating potential (B+) in receivers. A cost advantage is realized since the B+ filter may employ a resistance-capacitance (R.C.) type filter rather than the inductance-capacitance (L.C.) filter usually necessary when only half-wave rectification is used. A preferred embodiment of the present invention combines an instant-on feature which provides full-wave rectified direct current to the filaments during operation with a full-wave rectifier power supply circuit in an economical system which reduces the raster movement problem.

A circuit embodying the present invention includes means for producing a full-wave rectified voltage which is coupled to the filament string of the vacuum tube television receiver, and to the direct operating voltage circuit. Switching means are provided to convert the full-wave rectified voltage coupled to the filaments during normal operation to half-wave rectified voltage during a standby mode of operation.

FIG. 1 is a block diagram of a television receiver of the type including vacuum tubes which are illustrated diagrammatically in several of the stages.

FIG. 2 is a schematic circuit diagram showing the direct voltage supply used to power the receiver shown in FIG. 1. The diagram includes the filament string for the vacuum tubes of FIG. 1 and the instant-on feature of the present invention.

FIG. 3 is a schematic diagram illustrating an alternative embodiment of the present invention which can be substituted in the circuit shown in FIG. 2.

Referring now to the television receiver of FIG. 1, an antenna 10 receives composite television signals including audio, video, and synchronizing signals and couples these signals to the tuner 20. The tuner 20 includes a radiofrequency amplifier with a vacuum tube 22 having a filament 21 and local oscillator and mixer stages which incorporate a dual purpose

vacuum tube 24 having a filament 23. The tuner 20 amplifies the incoming composite signals and converts these signals to lower intermediate frequency (I.F.) signals which are then coupled to the I.F. section 25 of the television receiver. I.F. stage 25 includes two amplifier stages having vacuum tubes 26 and 28 with filaments 27 and 29 respectively. The I.F. stage 25 amplifies the frequency converted composite signals and couples them to the video and automatic gain control (A.G.C.) stage 30 of the receiver which includes a vacuum tube 32 having a filament 31 and which is of the dual purpose type. The triode section of vacuum tube 32 is utilized in a conventional keyed type A.G.C. circuit configuration. A.G.C. signals are coupled to the tuner 20 and I.F. stages 25 in a conventional manner. The video stage includes a video detector (not shown) for producing video frequency signals from the composite television signals. The pentode section of tube 32 is utilized as video output amplifier, and amplified video signals therefrom are coupled to a control element 34 of a kinescope 35 having a filament 33.

Amplifier stage 40 is coupled to the video amplifier 30 to receive synchronization and audio signals. Included in stage 40 is a dual purpose vacuum tube 42 having a filament 41. The pentode section of tube 42 is utilized as an audio I.F. amplifier, and the amplified audio I.F. signals are coupled to the audio detector and output stage 45. A dual purpose pentode tube 48 having a filament 47 detects the audiofrequency components of the audio I.F. signal, amplifies the resulting audio signals; and couples them to a speaker 49 to reproduce the audio portion of the television program.

The synchronizing signals coupled to stage 40 are amplified by the triode amplifier and are coupled to sync. separator stage 50 which separates the horizontal and vertical sync. components and couples them to the horizontal oscillator stage 55, and to the vertical oscillator stage 65 respectively. The horizontal oscillator includes a vacuum tube 58 having a filament 57. Horizontal frequency (15,734 Hz.) signals developed by the oscillator are coupled to the horizontal output stage 60 which includes a horizontal output tube 62 having a filament 61 and a damper diode 64 having a filament 63. The horizontal output stage 60 provides the horizontal deflection current by means of interconnection X-X, to a horizontal yoke 36 associated with the kinescope 35. Likewise the vertical oscillator and output stage 65 provides the vertical deflection current by means of interconnection Y-Y, to a vertical yoke 38 also associated with the kinescope 35. Having described the receiver which includes several vacuum tube stages and which is typical of many receiver types, attention is directed to FIG. 2.

In FIG. 2 there is illustrated the power supply for providing the direct operating potential (B+) to the various stages of the receiver of FIG. 1, also shown is the series filament string which is supplied with operating power in the unique manner to be described.

In the figure, line voltage is supplied to power transformer 75 by means of a power switch 70. This switch will normally be in the closed position since the instant-on feature is utilized to activate and deactivate the receiver. The transformer 75 has a bridge rectifier circuit comprising diodes 71, 72, 73, and 74 coupled across its secondary winding. A switch section 80a comprising one pole of a double-pole single-throw switch 80 is shown coupled in series with diode 74. Switch 80a could, however, be coupled in series with any of the diodes 71, 72, 73, or 74. An output terminal A is coupled by means of a second switch section 80b comprising the other pole of switch 80 to the B+ output terminal via a diode 91 and a filter network including capacitors 92 and 94 and a resistor 93. Terminal A is further coupled to the series string of filaments by means of a voltage dropping resistor 81. The numerals associated with the filaments shown in FIG. 2 correspond to the numerals accompanying the filaments in the vacuum tubes of FIG. 1. Several filter components including capacitors 82, 83, 85, 86, 87, 89, and 90; a resistor 84; and an inductor 88 are included as shown in the filament string to provide the desired filtering to each tube during operation.

In operation, the circuit provides power to the receiver in the following manner. With the switch 70 closed transformer 75 provides alternating voltage AC to the bridge circuit including diodes 71, 72, 73, and 74. When the receiver is in the "on" condition, i.e., being operated, switch 80 will also be closed thus ganged switch sections 80a and 80b will be in the closed position. The bridge operates in a conventional manner to produce a full-wave rectified voltage waveform at output terminal A. The full-wave rectified current is coupled by means of closed switch section 80b of switch 80 to the B+ filter and provides the operating direct current DC power to the receiver. Diode 91 conducts the charge the input filter capacitor 92 while also preventing the accumulated charge on this capacitor from leaking back through the filament string thereby lowering the B+ output voltage. Full-wave rectified current from terminal A is coupled to the series filament string to power the vacuum tube filaments. For standby operation switch 80 is opened and switch section 80b disconnects the B+ filter from terminal A thereby turning off the operating DC power to the receiver. Simultaneously, switch section 80a is opened and the bridge rectifier develops one-half wave rectified direct current to terminal A as diodes 72 and 73 conduct. In this mode of operation the conduction path including diode 71, transformer 75 secondary and diode 74 is broken and only one-half wave rectified voltage will appear at terminal A. The average power delivered to the filaments is therefore reduced to approximately one-half which is sufficient to maintain them in the desired standby condition. Although switch section 80a of switch 80 is illustrated serially coupled to diode 74 it is easily seen that the circuit operates equally well with the switch serially coupled to any of the diodes in the bridge rectifier. It is noted that transformer 75 will provide isolation to the receiver chassis which from the AC line can be operated as a "cold chassis;" an advantage when a metal cabinet is being used to house the receiver. The invention, however, has equal applicability to receivers which operate directly off the powerline without incorporating a power transformer such as transformer 75 shown in FIG. 2.

FIG. 3 illustrates an alternative embodiment of the present invention wherein a center tapped transformer 100 and two diodes 102 and 104 replace the bridge circuit of FIG. 2. Point A of FIG. 3 is coupled to the same point as terminal A in FIG. 2. Switch 105 is the same as switch 80 pole 80a in FIG. 2. In operation, switch 105 is closed and full-wave rectified voltage appears at terminal A. In the standby mode switch 105 is opened thereby reducing by one-half the power supplied to the filaments via terminal A. It is seen that switch 105 can be placed in series with either of diodes 102 or 104.

The following circuit parameters were utilized in the 50 preferred embodiment shown in FIG. 2.

Transformer	75	approximately 1:1 turns ratio
Diodes	71,72,73,74,91	IN 4004
Resistors	81	27 ohms
	84	6.8 ohms
	93	62 ohms
Capacitors	82	1,000 picofarads
	83	1,000 picofarads
	85	1,000 picofarads
	86	0.01 microfarads
	87	1,000 picofarads
	89	1,000 picofarads
	90	1,000 picofarads
	92	250 microfarads
	94	400 microfarads

15

What is claimed is:

1. A power supply for electronic apparatus including at least one vacuum tube with a filament comprising:
means for providing source of alternating voltage,
rectifying means coupled to said source of alternating voltage
to develop therefrom a full-wave rectified voltage
between a pair of output terminals,
means for connecting said vacuum tube filament between
said output terminals, and
switching means coupled in circuit with said rectifying
means for converting the voltage developed between said
output terminals to half-wave rectified voltage during a
standby mode of operation.
2. A circuit is defined in claim 1 wherein said supply means
comprises a transformer having a primary winding adapted to
be coupled to a source of alternating voltage and a secondary
winding for developing alternating voltages of opposite polarities
at opposite ends of said secondary winding.
3. A circuit is defined in claim 2 wherein said transformer
includes a grounded center tap secondary winding.
4. A circuit is defined in claim 3 wherein said rectifying
means comprises at least two diodes, each coupled to one of
said opposite ends of said secondary winding and to said output
terminal to provide a full-wave rectified voltage at said
output terminal, and
said switching means comprises a switch serially coupled
with one of said diodes.
5. A circuit is defined in claim 1 wherein said rectifying
means comprises a full-wave bridge having a diode in each leg
of said bridge and said switching means comprises a switch
coupled in series with a diode in any one leg of said bridge.
6. A power supply comprising:
a full-wave bridge rectifier circuit having input and output
terminals and at least one rectifier in each leg of said circuit,
said input terminals being adapted to be coupled to a source of alternating voltage,
means for coupling said output terminals to at least one
vacuum tube filament to provide power thereto, and
switching means coupled in series with one rectifier contained
in said bridge rectifier for providing a full-wave
rectified voltage at said output terminal when said
switching means is in a first state and a half-wave rectifier
voltage at said output terminal when said switching means
is in a second state.
7. A circuit as defined in claim 6 wherein said switching
means presents a closed circuit in said first state and an open
circuit in said second state.
8. A circuit as defined in claim 6 and further including:
further switching means operable in synchronism with said
switching means for coupling said output terminal to a
direct current power supply filter circuit when said
switching means is in said first state.
